UNITED STATES PATENT OFFICE.

JOSEPH SZAFKA, OF PHILADELPHIA, PENNSYLVANIA.

WINE PRESS.

Application filed August 11, 1920. Serial No. 402,742.

To all whom it may concern:

Be it known that I, JOSEPH SZAFKA, a citizen of the United States, residing at Philadelphia, in the county of Philadelphia and 5 State of Pennsylvania, have invented new and useful Improvements in Wine Presses, of which the following is a specification.

My invention relates to a new and useful improvement in wine presses for extracting 10 juices from fruit or the like by pressure, and has for its object to provide an exceedingly simple and effective device of this description which may be readily adjusted for filling, emptying or for cleansing.

15 A further object of my invention is to provide a specially constructed receptacle or receiver for the fruit.

A still further object of my invention is to provide special means for putting a split 20 nut into and out of engagement with the operating screw.

A still further object of my invention is to provide for counterbalancing the operating screw and the parts carried thereby.

25 With these ends in view, this invention consists in the details of construction and combination of elements hereinafter set forth and then specifically designated by the claims.

30 In order that those skilled in the art to which this invention appertains, may understand how to make and use the same, I will describe its construction in detail, referring by numerals to the accompanying drawings forming a part of this application, in which:—

Fig. 1, is a plan view of a press made in accordance with my improvement.

Fig. 2, is a side elevation of Fig. 1, the tub 40 being in section.

Fig. 3, is an enlarged horizontal section at the line 3—3 of Fig. 2.

Fig. 4, is a detail view of the means for attaching the counterbalancing cable to the 45 operating screw.

Fig. 5, is a detail perspective of the latch mechanism for locking the cross bar and parts carried thereby in normal position.

In carrying out my invention as here embodied, 1 represents a base upon which is supported the tub 2, said tub having a series of slats 3 located upon the bottom thereof, and upon these slats is set the receptacle or cylinder 4. This receptacle is made of 55 wire gauze of sufficient strength to with-

stand the outward pressure of the fruit when the juice is being extracted therefrom; and as said juice is forced out of the fruit it will flow into the tub and through the places in the slate 3 to the drain pipe 5 from whence it may be conveyed in any suitable vessel. The cylinder 4 is provided with handles 6 by means of which it may be lifted out of the tub or placed therein.

Within the tub are formed the bosses 7 into which the lower ends of the standards 8 and 9 are threaded, the standard 8 having pivoted to the upper end thereof the cross bar 10, the opposite end of said cross bar carrying a head 11 in which is formed an open eye 12 for engagement with the upper end of the standard 9 when the head 11 passes between the collar 13 and the nut 14. This head has a spring actuated latch 15 the lower end of which is so formed as to engage the extension 16 formed with the collar 13 thereby locking the cross bar 10 in its normal position.

17 represents a casing or box which is formed with or secured to the cross bar 10 and in this casing is housed a split nut 18; each section of said nut having an eccentric cross bar 19 passing through a suitable opening formed therein, the ends 20 of said eccentric cross bar being journaled in the side walls of the box. Upon one of the ends 20 of each of the eccentric cross bars is secured a segmental gear 21, said gears meshing together as clearly shown in Fig. 2, one of said segments having a handle 22 formed therewith or secured thereto so that by the manipulation of this handle the eccentric cross bars will be forced to open or close the sections of the split nut as will be readily understood.

23 represents the operating screw which passes through the hub 24 formed upon the cross bar 10 and also through the box or casing 17 and is surrounded by the sections of the split nut 18 in such manner that when the eccentric cross bars 19 are thrown into proper direction this split nut will engage the operating screw and be normally held in such engagement by the springs 25 set between the sections of the split nuts and the walls of the box as clearly shown in Fig. 3. The lower end of the operating screw 23 is swivelled to the plunger 26 by having a flange 27 formed thereon, said flange fitting in the hub 28 formed with the plunger and 105 110

a nut surrounding said screw and threaded into said hub. By this arrangement the operating screw will be free to revolve while the plunger is held against rotation and the 5 rotation of the operating screw is effected by a spiral gear 30 which is journaled in the hub 24 of the cross bar 10, said gear being splined to the operating screw as indicated at 31. Thus when this spiral gear is 10 revolved the operating screw will also be revolved and when the split nut is in engagement said screw and the revolving of the latter will cause it to move downward or upward as the occasion may be.

15 32 is a spiral pinion which meshes with the spiral gear 30, said pinion being journaled between the bearings 33 carried by the cross bar 10 having secured to one end thereof the hand wheel 34 carrying the crank 20 handle 35 by which the spiral pinion may be revolved in either direction for transmitting a rotary motion to the operating screw through the spiral gear 30.

In practice it is intended that the downward movement of the plunger be brought about by the revolving of the operating screw above described when the split nut is in engagement therewith since it is during 25 this movement that it is necessary to transmit considerable power to the plunger for extracting juice from the fruit within the receptacle, but by the upward movement of the plunger should be accomplished quickly and requiring the transmission of more 30 power therethrough I provide means for counterbalancing or slightly overbalancing said plunger and the parts carried thereby. This counterbalancing is effected by a cable 36 which runs over the pulleys 37 and 38 35 mounted upon the bracket 39, said bracket being secured to the pivoted end of the cross bar 10 as indicated at 40. This cable is attached to the upper end of the operating screw by a disc 41 with which are formed 40 the ears 42 having a pin 43 passing through said ears to which the end of the cable is attached, said disc being set in a threaded hole or recess 44 and retained therein by the nut 45 which is threaded into said hole 45 or recess the cable passing through a suitable hole in said nut. A series of balls 46 50 are interposed between the disc and the lower end of the nut 45 so as to reduce the friction between these two elements thus permitting the operating screw to revolve without revolving the cable. Upon the opposite end of the cable is suspended a weight 47 sufficiently heavy to counterbalance or slightly overbalance the operating 55 screw and plunger.

From the foregoing description the opera-

tion of my improved press will be obviously as follows:—

The fruit or other material to be pressed being placed in the cylinder 4, said cylinder 65 is set within the tub upon the slats 3 and the plunger inserted in the upper end of said cylinder when by revolving the hand wheel 34 the operating screw will force the plunger downward within the cylinder 70 causing the latter to exert sufficient pressure upon the fruit to squeeze the juice therefrom. When this has been accomplished the proper manipulation of the hand lever 22 will disengage the sectional nut 75 from the operating screw within the plunger and consequently the operating screw may be readily and quickly elevated by grasping the handle 48 and drawing upward thereon the counterbalance weight 47 facilitating 80 this operation. Now by disengaging the latch 15 from the extension 16 of the collar 13 the cross bar 10 may be swung out of engagement with the standard 9 carrying with it the operating parts of the 85 apparatus and leaving the cylinder free to be removed from the tub; it being noted that the bracket swinging with the cross bar 10 maintains the cable in its proper relative position to the operating screw. 90

To reset the press for a succeeding operation it is only necessary to place the fruit to be acted upon within the cylinder, set latter within the tub swing the cross bar 10 back to its normal position when it will be latched as before described, manipulate the handle 22 so as to engage the sectional nut with the operating screw and then 95 revolve the hand wheel 34 to bring about the downward movement of the plunger. 100

Of course I do not wish to be limited to the exact details of construction as herein shown as these may be varied within the limits of the appended claim without departing from the spirit of my invention. 105

Having thus fully described my invention, what I claim as new and useful is:—

A press of the character stated including an operating screw carrying a plunger, said operating screw having a threaded recess 110 in its upper end, a disc set in said recess, an axially bored nut threaded into the recess, a cable having a counterbalance weight on one end, the other end of said cable passing through the bore of said nut 115 and attached to said disc, and a series of balls interposed between the lower end of the nut and said disc for the purpose stated.

In testimony whereof, I have hereunto affixed my signature.

JOSEPH SZAFKA.
